DOOR LOCK

Henry D. Rolph, Stamford, Conn., assignor to
The Yale & Towne Manufacturing Company,
Stamford, Conn., a corporation of Connecticut

Application February 17, 1940, Serial No. 319,450

11 Claims. (Cl. 70—146)

This invention relates to a door lock, more especially to a door lock of the tubular type.

More particularly, my invention relates to a lock of the type having a latch bolt housing adapted to be inserted into a bore extending inwardly from the edge of a door, and a latch bolt operating assembly inserted through a transverse bore in the door and into engagement with the latch bolt housing.

The door lock of my invention is somewhat related to that shown in the application of Charles Ledin for a Lock, Serial No. 228,222, filed September 2, 1938, now Patent No. 2,226,499, granted December 24, 1940. As in the Ledin application, I use an inside knob equipped with a push button and an outside knob adapted to be locked against operation when the push button is depressed. Rotation of the inside knob of my lock moves the push button out of its depressed position, and releases the outside knob for free rotation. The important feature of my invention is the arrangement of the means whereby the push button and push rod with which it is connected are operated, and in turn control the operation of the lock.

More specifically, my invention utilizes a spindle surrounding the push rod and to which the inside and outside knobs of my lock are secured. Preferably, the spindle is rotated with the push rod by the inside and outside knobs for retracting the latch bolt, a portion of the push rod itself being utilized preferably for retracting the latch bolt. A feature of my invention is the utilization of the push rod for locking the spindle against rotation through the entry of a portion of the push rod into interlocking relation with means in the new and novel latch bolt housing of my lock. The inside knob, while adapted to rotate the spindle, is capable of some motion relatively to the spindle, and this motion is utilized as in the Ledin application, for moving the push rod out of locking position.

A further feature of my invention is the arrangement of a lock in the outside knob for moving the push rod into release position by rotation of the key plug of the lock in a predetermined manner. It is a further feature of my invention that the lock does not in any way interfere with the operation of the outside knob when the push rod is in release position.

I have thus described generally the most important features of my invention, but it will be appreciated upon a reading of the specification that the lock which I have herein disclosed has other important features which should be in-

cluded in the patent monopoly to be granted me.

Referring now to the drawings, Fig. 1 is a horizontal section showing the lock of my invention applied to a door and with the latch bolt in locking position. Fig. 2 is a front view of the outside knob, and Fig. 3 is a front view of the inside knob. Fig. 4 is a section taken along lines 4—4 of Fig. 1. Fig. 5 is an enlarged section taken substantially along the same lines as Fig. 4. Fig. 6 is a section taken along lines 6—6 of Fig. 1. Figs. 7, 8 and 9 are sections taken along lines 7—7, 8—8 and 9—9, respectively, of Fig. 4. Figs. 10, 11 and 12 are sections taken along lines 10—10, 11—11, and 12—12, respectively, of Fig. 5. Fig. 13 is an exploded view of the lock assembly showing the several parts thereof.

Referring now more particularly to the drawings and especially Fig. 1, I show a latch bolt housing 10 mounted in a bore 11 extending into the door from the edge thereof. The housing 10 contains a latch bolt 12 which is adapted to enter the strike 13 secured to the jamb 14 of the door. The latch bolt is projected into locking position by a spring 15, whose relation to the latch bolt is probably best shown in Fig. 6.

Referring now to Fig. 6, the tail of the latch bolt 12 is designated by reference numeral 16 and terminates in lugs 17 and 18. Lug 17 cooperates with a retracting cam 19, while lug 18 cooperates with an oppositely related retracting cam 20. The retracting cam 19 is pivoted about a pin 21, while the retracting cam 20 is pivoted about a pin 22 extending from the housing 10. A rollback 23 having projecting lugs 23a and 23b is mounted within the latch bolt housing 10, and when rotated in a clockwise or counter-clockwise direction, will actuate one or the other of the retracting cams 19 and 20 to retract the latch bolt through one or the other of the lugs 17 and 18 of the latch bolt tail 16.

Referring now to Fig. 13, there is there illustrated the rollback 23, and to each side thereof there is shown a plate 24. Each plate 24 is equipped with an abutment 25 on the inside thereof on which the rollback 23 is mounted through the intermediary of the countersunk portions 26 formed on each side thereof. Each of the plates 24 is self-retained against rotation within the casing 10, and is maintained against sliding due to the coaction of its part 25 with the rollback 23.

It will be well to note at this point that the rollback 23 is formed with a groove 27, and that each of the portions 25 of the plates 24 is grooved

at 25a. The rollback 23 has an additional groove 27a so that it may be readily reversed. As will be readily apparent also, from the description of the latch bolt housing and the mechanism therein contained, the entire assembly so far described is reversible.

I shall now describe the push rod, or control rod as it may be called, which is probably best illustrated in Fig. 13 where it is designated by reference numeral 28. A push button 29 is threaded on to the screw threaded pin 30 formed integrally with the push rod 28 so that, in effect, the push button and push rod are one piece after assembly. The push button 29, of course, lies within the inside knob, designated by reference letter K¹, while the other end of the push rod lies in the shank sleeve of the outside knob, designated by reference letter K². The outside end of the push rod 28 carries a somewhat less than semi-circular cam portion 31 in which is formed a cam groove 32, it being the function of the cam groove 32 to cooperate with a lug hereinafter described, to effect longitudinal movement of the push rod in a direction reverse to the movement imparted thereto by depression through push button 29.

Integral also with the push rod 28 are a release pin 33 and the rollback operating lug 34. This lug 34 is adapted to lie within the slot 27 of the rollback 23 to operate the rollback through rotation of the push rod 28. It is also a function of the lug 34 to lie within one of the slots 25a of the abutment 25 of one of the plates 24 to lock the push rod 28 against rotation, as will be indicated presently. Surrounding the push rod 28 is what I term a spindle 35 which has formed therein a slot 36 in which ride the pin 33 and the lug 34 of the push rod for maintaining the push rod and spindle against rotation relatively to one another.

A ball 37 is projected by spring 37a from the bore 37b of the push rod into a bore 38 or a bore 39 of the spindle 35, thus yieldingly retaining the push rod 28 in one or the other of two different longitudinal positions relatively to the spindle 35, it being obvious that while the push rod 28 is not rotatable relatively to the spindle 35, it is slideable relatively thereto. While there are further features of construction on both the push rod 28 and the spindle 35, they will be described with relation to the remaining parts of the lock herein-after.

Referring now to the inside knob K¹, it will be noted that it is equipped with a shank portion 40 in which are mounted the parts 41, 42, and 43, shown best in the exploded view of Fig. 13. In assembling the parts 41, 42 and 43 relatively to the inside knob shank 40, the cam part 43 is first inserted within the part 42 so that a hole 43a of the part 43 lines up with the hole 42a of the part 42. The two parts 42 and 43 when assembled within the shank 40 have their bores 42a and 43a aligned with bore 40a of the knob shank 40, and are secured in that position by a screw 44. Thus, upon assembly, the knob shank 40, the part 42 and the cam part 43 will be fixed against any rotation relatively to one another, and will, in effect, be one piece. For the purposes of the invention, it may therefore be considered that the parts 40, 42 and 43 are integral.

Before the part 42 is inserted into the knob shank 40, the part 41, which I shall term the spindle actuator, is moved over the smaller end sleeve portion 45 of the part 42. The screw 46 is threaded into the bore 41a of the spindle actua-

tor 41 and protrudes into a slot 47 in the portion 45 of the part 42. In this way, the knob K¹, together with its parts 42 and 43, is adapted for limited rotation relatively to the spindle actuator 41, as determined by the length of the slot 47, but is held against longitudinal movement relatively thereto.

A lug 48 extends from the spindle actuator 41 and occupies a position under a somewhat similar lug 49 extending from the part 42. A coil spring is wound about the portion 45 of the part 42 and has its ends 50 and 51 so arranged relatively to the overlying lug 49 of the part 42 and the underlying lug 48 of the spindle actuator 41, as to maintain the spindle actuator yieldingly in position, with the screw 46 centrally related to the slot 47, as is probably best illustrated in Fig. 9.

It will be noted that the spindle actuator 41 is slotted as at 52 for the housing of a lug 53 depending downwardly from the spindle 35. Because of this relationship of the parts, it will be obvious that the spindle 35 is always held for rotation with the spindle actuator 41, and that therefore, the spindle actuator 41 is always maintained for rotation integrally with the push rod 28. The spindle 35 is slotted as at 54 for the entry of the end 54a of a screw 55 carried by the knob shank 40. It will be obvious that the screw 55 prevents longitudinal movement of the inside knob K¹ relatively to the spindle 35, but that rotation of the knob K¹ relatively to the spindle is possible within the limits of the slot 54. This limited rotation is the same as that allowed by the screw 46 relatively to the slot 47 of the part 42, and is of course resisted by the spring S, as has already been described.

It will be remembered that the push rod 28 is equipped with a release pin 33, which pin is adapted to cooperate with cam surfaces 56 formed on the cam part 43, as is probably best illustrated in Fig. 13. Also, the part 43 is rotatable with the knob K¹ and relatively to the push rod 28 and spindle 35 when the push rod is locked against rotation. Moreover, when the push rod 28 is depressed into locking position, the pin 33 lies opposite the cam surfaces 56, where the cam surfaces are relatively close together. The rotation of the knob K¹ as above set forth, will cause one of the cam surfaces 56 to coat with the pin 33 to move the push rod outwardly and into release position. This operation will be described more fully presently.

It may be well now to refer to Figs. 7, 8, 9 and 10 to better describe the relationship of the parts. Referring first to Fig. 7, we see the knob shank 40 into which is entered the screw 55, with the end portion 54a of the screw within the slot 54 of the spindle 35. The lugs 53 of the spindle is shown within the groove 52 of the spindle actuator 41. It is obvious here that the knob is rotatable relatively to the spindle but cannot move longitudinally relatively to the spindle. It is obvious also that the spindle 35 and the spindle actuator 41 are held against rotary movement relatively to one another. The push rod is shown by reference numeral 28, centrally located relatively to the assembly.

Referring now to Fig. 8, we see first the knob shank 40 surrounding the actuator 41. We see further the screw 46 threaded into the bore 41a of the actuator 41 and working in the slot 47 of the portion 45 of the part 42. We then see within the part 42 the spindle 35 and the ball 37 pressed by the spring 37a from push rod 28 into the bore 38 of the spindle 35 to maintain the

push rod 28 in its unlocking position relatively to the spindle.

Referring now to Fig. 9 once again, we see there the knob shank 40 surrounding the part 42. We see also the ends 50 and 51 of the coil spring S maintaining aligned the lugs 49 and 48 of the parts 42 and 41, respectively.

Before describing Fig. 10, it may be well to indicate through reference to Figs. 1 and 4, that in the unlocked position of the lock, the end of push button 29 forming part of the push rod 28 is maintained somewhat outwardly of the inside knob K¹. In this position of the parts, the pin 33 of the push rod 28, which protrudes through the slot 36 of the spindle 35, lies near the left hand portion of the opposite cam surfaces 56 of the cam part 43. When the push button 29 is depressed as shown in Fig. 5, the pin 33 is carried to the right hand end of the cam part 43, and therefore to a different position relatively to the cam surfaces 56, as will be apparent. This is the position of the parts also illustrated in Fig. 10, where we see the inside knob shank 40 in the interior of which is mounted the part 42, to which is fixed the cam part 43. The two cam surfaces 56 are shown with relation to the pin 33, it being obvious that when the cam part 43 and its cam surfaces 56 are rotated relatively to the pin 33, the pin 33 together with its push rod 28 will be moved back from the position of Fig. 5 to the position of Fig. 4.

Referring now to Fig. 11, the rollback 23 is shown with the retracting lug 34 of the push rod 28 within its slot 27. We see also the lug 23a extending from the rollback 23 into engagement with the latch bolt retracting cam 20. There is also shown one of the two plates 24.

I shall now describe the outside knob K² and its assembly relatively to the remaining parts. Mounted within the sleeve or shank portion 57 of the outside knob K² is a sleeve 58. This sleeve 58 has a bore 58a which, in the assembled relation of the parts, is adapted for alignment with a bore 59 of the spindle 35. A screw 60 is adapted to enter a bore 57a of the outside knob shank 57, the bore 58a of the sleeve 58 and the bore 59 of the spindle 35, with the end 60a of the screw 60 entering a slot 61 of the push rod 28. With the screw 60 thus inserted, it will be appreciated that the outside knob K² will be assembled through its shank 57 to the sleeve 58 and the spindle 35, so that the knob and spindle will rotate as a single unit and may be considered as though made of one piece.

The push rod 28, while capable of sliding movement relatively to the outside knob, as limited by the length of its slot 61, will be incapable of any rotary movement whatsoever relatively to the outside knob.

Mounted within the knob is a sleeve 62 having a pin 63 extending downwardly therefrom into a position where it can enter one end or the other of cam groove 32 formed in the cam portion 31 which was described as integral with the push rod 28. The inner end of the sleeve 62 is slotted as at 64 for cooperation with the lug 65 of the key plug 66 of a cylinder lock 67. Incidentally, the sleeve 58 has threaded holes 68 into which are inserted screws 69 which enter shallow bores 70 of the cylinder lock 67, thus securing the cylinder lock to the knob K², its sleeve 58, and the spindle 35.

I shall now describe the relationship of the parts in Fig. 12. There I have illustrated the outside knob shank 57 surrounding the sleeve 58,

which may be considered as part of the knob. The sleeve 62 is shown together with its pin 63 in its relation to the cam abutment 31 formed integrally with the push rod 28. The relationship of the parts illustrated in Fig. 12 is the same, of course, as the relationship of the parts illustrated in Fig. 5. Rotation of the sleeve 62 by the key plug in a counterclockwise direction, looking at Fig. 12, will bring the lug 63 into the end 32a of the cam groove 32, and further rotation of the sleeve will of course move the push rod to the left from its locking position of Fig. 5, all as will be quite apparent.

Having thus described the various parts of my invention and their relationship, I shall now attempt to point out their operating relationship by describing one complete operation of my locking mechanism. Referring to Figs. 1 and 4, where the outside knob K² is shown released, and the push button outwardly of the inside knob K¹, it will be noted that the retracting lug 34 of the push rod 28 protrudes through the slot 36 of the spindle 35 into the groove 27 of the rollback 23. The pin 33 of the push rod also protrudes through the slot 36 of the spindle 35, and is near the left end of the cam part 43 and its opposed cam surfaces 56.

The inside knob K¹ is capable of some rotary movement relatively to the spindle actuator 41, against the pressure of the spring S, as determined preferably by screw 46 lying in slot 47 of the part 42. Knob K¹ is, however, through co-operation of its screw 55 with the slot 54 of the spindle 35, incapable of any sliding movement relatively to the spindle and is therefore retained on the spindle. Rotation of the inside knob K¹ will first wind the spring S, and will then rotate the spindle actuator 41, which through co-operation with the lug 53 of the spindle, will rotate the spindle, and therefore the push rod 28 and lug 34, rotating the rollback 23 to retract the latch bolt 12. This movement will of course effect a rotation of the outside knob K² which, in effect, is integral with the spindle 35 and is incapable of any rotary movement whatsoever relatively to the push rod 28, all because of the operation of the screw 60 which holds in fixed assembly the shank 57 of the outside knob K², the sleeve 58, and the spindle 35. It will of course be remembered also that the end 60a of the screw 60 fits within the slot 61 of the push rod 28.

With the parts in the position of Figs. 1 and 4, should it be desired to lock the outside knob against rotation, it is merely necessary to depress the push button 29 into its position of Fig. 5. When this is done, the retracting lug 34 of the push rod moves out of the groove 27 of the rollback 23 and into the groove 25a of the portion 25 of one of the plates 24. It is obvious that in this position of the parts, the push rod and the spindle 35 will be incapable of any rotation whatsoever. Since the outside knob K² is, for all practical purposes, integral with the spindle 35, it also will be maintained against any rotation whatsoever.

Incidentally, the ball 31 extending from the push rod will have moved into cooperation with the hole 39 of the spindle 35, yieldingly maintaining the push rod and push button 29 in the position of Fig. 5. It will be well also to indicate that in the position of the parts in Fig. 5, the pin 33 extending downwardly from the push rod 28 through the slot 36 of the spindle 35 will lie at the right hand end of the cam part 43, and there-

fore opposite the right hand ends of the cam surfaces 56.

In this position of the parts, while the outside knob is locked against rotation because it is fixed to the spindle 35, the inside knob is capable of rotation relatively to the spindle 35 and the spindle actuator 41. Such rotation of the knob K¹ will rotate its shank 40, and therefore the parts 42 and 43, while the spindle actuator 41 remains stationary, being locked to the push rod 28 and the spindle 35 against rotation. This rotation of the knob and the cam part 43, will cause one or the other of the cam surfaces 56 to contact the pin 33, camming the push rod from the position of Fig. 5 to the position of Fig. 4, all as will be quite apparent.

In this way, when the outside knob is locked, should anyone attempt to retract the latch bolt from the inside, he will first release the outside knob. Further rotation of the inside knob will of course move the spindle actuator 41 and rotate the spindle to retract the latch.

I shall now describe the operation of the cylinder lock to release the outside knob when the parts are in the position of Fig. 5. It will be noted in Fig. 5 that with the outside knob locked, the cam groove 32 of the push rod is in the particular relation to pin 63 of the sleeve 62 already described. If the key plug 66 of the cylinder 61 be now rotated, the lug 65 through cooperation with the slot 64, will rotate the sleeve 62 relatively to the knob, causing the pin 63 to enter the end 32a of the cam groove 32 to effect a movement to the left of the push rod 28. This brings the push rod into the position of Fig. 4, in which position the outside knob will once again be free for rotation with the spindle to retract the latch bolt.

I believe that the operation of the particular form of my invention here described will now be clear to those skilled in the art. It should be appreciated that many changes in the construction of the lock of my invention will readily occur to those skilled in the art. I do not wish, therefore, to be limited in my monopoly to the particular structure I have herein shown as best embodying my invention.

I claim:

1. In a lock of the class described, a hollow spindle, an outside knob fixed to one end of the spindle, an inside knob mounted on the other end of the spindle, means whereby said inside knob rotates a predetermined degree relatively to said spindle prior to transmitting rotation to said spindle, a rod within said spindle and movable longitudinally thereof, a push button fixed on the inside end of said rod extending through an opening in the inside knob whereby it may be depressed, means whereby said rod when depressed locks said spindle against rotation, and means whereby rotation of said inside knob said predetermined degree relatively to said spindle moves said rod out of its depressed position.

2. In a lock of the class described, a hollow spindle, an outside knob fixed to the spindle at one end, an inside knob mounted on the other end of the spindle, means whereby said inside knob moves relatively to said spindle for a short distance and then moves integrally with said spindle, a rod within said spindle and movable longitudinally thereof, a push button on the inside end of said rod extending through an opening in the inside knob whereby it may be depressed, means whereby said rod when depressed

locks said spindle against rotation, and means whereby rotation of said inside knob relatively to said spindle moves said rod out of its depressed position.

5. 3. In a lock of the class described, a hollow spindle, an outside knob fixed on said spindle, an inside knob mounted on the spindle, means whereby said inside knob rotates a predetermined degree relatively to said spindle prior to transmitting rotation to said spindle, a rod within said spindle and rotatable therewith while movable longitudinally thereof, a latch bolt, means whereby said rod when rotated with said spindle retracts said latch bolt, means whereby said rod when depressed locks said spindle and said rod against rotation, a push button on the inside end of said rod extending through an opening in the inside knob whereby said rod may be depressed, and means whereby rotation of said 10 inside knob said predetermined degree relatively to said spindle moves said rod out of its depressed position.

- 20 4. In a lock of the class described, a hollow spindle, an outside knob fixed to the spindle at one end, an inside knob mounted on the other end of the spindle, means whereby said inside knob moves relatively to said spindle for a short distance and then moves integrally with said spindle, a rod within said spindle and rotatable therewith while movable longitudinally thereof, a latch bolt, means whereby said rod when rotated with said spindle retracts said latch bolt, means whereby said rod when depressed locks said spindle and said rod against rotation, a push 25 button on the inside end of said rod extending through an opening in the inside knob whereby it may be depressed into spindle locking position, and means whereby rotation of said inside knob relatively to said spindle moves said rod out of its depressed position.

- 30 5. In a lock of the class described, a hollow spindle, an outside knob secured on one end of said spindle, an inside knob mounted on the other end of said spindle, a rod within said spindle, a lug on said rod protruding through a slot in the spindle whereby said rod and spindle rotate as a unit while allowing sliding movement of said rod in said spindle, a latch bolt, means whereby said lug retracts said latch bolt through rotation of said spindle when said rod is in one position relatively to said spindle, means whereby said lug locks said spindle and rod against rotation when said rod is in a second position relatively to said spindle, means secured to said 45 rod and extending through an opening in the inside knob whereby said rod is moved to its second or locking position, said inside knob having a part thereof fixed to said spindle and a knob portion capable of limited rotation relatively to said part, and means whereby said knob portion moves said rod from locking to release position when said limited rotation is imparted to said knob portion.

- 60 6. In a lock of the class described, a hollow spindle, an outside knob fixed to one end of said spindle, a rod mounted within said spindle and for longitudinal sliding movement relatively thereto, a latch bolt, means whereby said knob and spindle and rod rotate together to retract said latch bolt, means whereby said rod is moved longitudinally in said spindle to lock said spindle and outside knob against rotation, a lock within said outside knob, a key plug in said lock rotatable relatively to said knob, and a pin and groove connection between said key plug and

rod whereby rotation of said key plug moves said rod longitudinally of said spindle and out of locking position.

7. In a lock of the class described, a hollow spindle, an outside knob fixed to one end of said spindle, an inside knob mounted on the other end of said spindle, means whereby said inside knob rotates a predetermined degree relatively to said spindle prior to transmitting rotation to said spindle, a rod mounted within said spindle and for longitudinal sliding movement relatively thereto, a latch bolt, means whereby said outside knob and spindle and rod rotate together to retract said latch bolt, a push button on the inside end of said rod protruding through a bore in the inside knob whereby said rod is moved longitudinally in said spindle, means whereby said rod when so moved locks said spindle and outside knob against rotation, means whereby rotation of said inside knob said predetermined degree relatively to said spindle moves said rod out of locking position, a lock within said outside knob, a key plug in said lock rotatable relatively to said knob, a cam groove formed on the said rod, and means including a pin adapted to enter said groove, rotated by said key plug to move said rod longitudinally to release position.

8. In a lock of the class described, a hollow spindle, an outside knob fixed to one end of said spindle, an inside knob mounted on the other end of said spindle, a rod mounted within said spindle and for longitudinal sliding movement relatively thereto, a latch bolt, means whereby said knob and spindle and rod rotate together to retract said latch bolt, a push button on the inside end of said rod protruding through a bore in the inside knob whereby said rod is moved longitudinally in said spindle to lock said spindle and outside knob against rotation, a lock within said outside knob, a key plug in said lock rotatable relatively to said knob, a cam groove formed on the said rod, a rotatable sleeve in said outside knob having a pin for operating in said groove, and means whereby said key plug when rotated, rotates said sleeve to move the rod to release position by engagement of its pin with said cam groove.

9. In a lock of the class described, a hollow spindle, an outside knob fixed to one end of said spindle, an inside knob mounted on the other end of said spindle, a rod mounted within said spindle and for longitudinal sliding movement relatively thereto, a latch bolt, means whereby

said outside knob and spindle and rod rotate together to retract said latch bolt, a push button on the inside end of said rod protruding through a bore in the inside knob, whereby said rod is moved longitudinally in said spindle to lock said spindle and outside knob against rotation, a lock within said outside knob, a key plug in said lock rotatable relatively to said knob, a cam groove formed on the said rod, and means including a pin adapted to enter said groove, rotated by said key plug to move said rod longitudinally to release position.

10. In a lock of the class described, a hollow spindle, an outside knob fixed to one end of said spindle, an inside knob mounted on the other end of said spindle, a rod mounted within said spindle and for longitudinal sliding movement relatively thereto, a latch bolt, means whereby said knob and spindle and rod rotate together to retract said latch bolt, a push button on the inside end of said rod protruding through a bore in the inside knob, whereby said rod is moved longitudinally in said spindle to lock said spindle and outside knob against rotation, a lock within said outside knob, a key plug in said lock rotatable relatively to said knob, cam and groove connecting means between said key plug and rod adapted for engagement in the locked position of said rod and in the unlocked position of said rod, whereby rotation of said key plug moves said rod longitudinally in said spindle.

11. In a lock of the class described, a hollow spindle, an outside knob fixed to one end of the spindle, an inside knob mounted on the other end of the spindle, means whereby said inside knob rotates a predetermined degree relatively to said spindle prior to transmitting rotation to said spindle, a rod within said spindle and movable longitudinally thereof, a push button fixed on the inside end of said rod extending through an opening in the inside knob whereby it may be depressed, means whereby said rod when depressed locks said spindle against rotation, means whereby rotation of said inside knob said predetermined degree relatively to said spindle moves said rod out of its depressed position, a lock within said outside knob, a key plug in said lock rotatable relatively to said knob, and means between said key plug and rod whereby rotation of said key plug moves said rod out of its depressed position.

HENRY D. ROLPH.
